(74) Attorney, Agent, or Firm — Knobbe, Martens, Olson & Bear, LLP

(57) **CLAIM**

The ornamental design for a flying toy, as shown and described.

DESCRIPTION

FIG. 1 is a front, top, and right side perspective view of a flying toy embodying my new design.

FIG. 2 is a top view thereof.

FIG. 3 is a bottom view thereof.

FIG. 4 is a left side view thereof.

FIG. 5 is a right side view thereof.

FIG. 6 is a front view thereof; and,

FIG. 7 is a back view thereof.

1 Claim, 7 Drawing Sheets
